P. T. COFFIELD.

RECIPROCATING FLUID PRESSURE MOTOR.

APPLICATION FILED JAN. 13, 1909.

1,049,456.

Patented Jan. 7, 1913.

UNITED STATES PATENT OFFICE.

PETER T. COFFIELD, OF DAYTON, OHIO, ASSIGNOR TO THE COFFIELD MOTOR WASHER COMPANY, OF DAYTON, OHIO.

RECIPROCATING FLUID-PRESSURE MOTOR.

1,049,456.

Specification of Letters Patent.

Patented Jan. 7, 1913.

Application filed January 13, 1909. Serial No. 472,015.

To all whom it may concern:

Be it known that I, PETER T. COFFIELD, citizen of the United States, residing at Dayton, in the county of Montgomery and State of Ohio, have invented certain new and useful Improvements in Reciprocating Fluid-Pressure Motors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in fluid-pressure reciprocating motors designed for furnishing power for the operation of a variety of machines usually operated by hand, such for example, as washing machines.

The object of the invention is to provide a motor of the above type which combines simplicity and efficiency to the desired extent, and owing to the simplicity of which, it is adapted to be placed in the hands of persons unskilled in mechanical knowledge.

To the foregoing ends, springs or their equivalents are entirely eliminated as means for imparting any of the valve movements.

Preceding a detailed description of the invention, reference is made to the accompanying drawings, of which—

Figure 1, is a longitudinal sectional view of a motor embodying my improvements. In this view, the piston is shown approaching the end of one of its strokes with the inlet valve at the initial point of movement. Fig. 2, is a sectional elevation of one end of the motor showing the piston at one end of its stroke or just beginning its reverse movement. The inlet valve in this view is shown to be completely reversed from the position shown in Fig. 1. Fig. 3, is a cross sectional view through the valves and piston on the line $a-a'$ of Fig. 1. Fig. 4, is a detached view of the inlet valve with one of its tubular extensions shown in section.

In a detail description of the invention,

similar reference characters indicate corresponding parts.

The cylindrical body 1 of the motor is inclosed at each end by a head or abutment 2 2', and movable within said cylinder is a piston 3 provided with non-communicating chambers 4 and 5, chamber 4 being the inlet chamber for the motive fluid, and chamber 5 being the exhaust chamber. Extending from these chambers on opposite sides of the piston, are hollow piston rods 6 and 9, the former rod communicating with the inlet chamber 4 and the latter rod communicating with the exhaust chamber. These tubular piston rods extend out of the motor cylinder through stuffing boxes 7 in the cylinder heads or abutments 2 2'. The tubular piston rod 6 connects with the faucet or other connection (not shown) through which the motive fluid is introduced, and rod 9 connects with an outlet pipe 10, which in turn, is connected to a flexible pipe or other means (not shown) to carry off the water. Also connected with the pipe 9 is a rack 11, a portion of which is broken off, forming the means for transmitting the power to the machine to be operated.

Mounted in the exhaust chamber 5 and having seats on the outer sides of the piston, are double puppet exhaust valves 12 which are connected by vanes 13 or otherwise, and have stems 14 which alternately engage the cylinder heads or abutments 2 2' in unseating said valves at each end of the piston stroke. After said valves are unseated, their movement is completed by the live fluid to be again referred to.

Mounted within the inlet chamber 4, is a double puppet inlet valve 15 adapted to alternately seat on seats on the interior of the piston. This inlet valve has tubular extensions 16 16' which form auxiliary valves for unbalancing said inlet valve and thereby insuring a complete stroke of said inlet valve by the live fluid. The tubular extensions 16 and 16' are connected to the valve and are provided with ports to permit the live fluid to pass from the chamber 4 into said tubular extensions alternately. The ends of said

tubular extensions alternately engage the cylinder heads or abutments 2 2' as the piston approaches said heads or abutments, and the slight continued movement of the piston thereafter, unseats said valve and allows the live fluid which has entered said tubular extension, to exert a pressure against the cylinder head or abutment and thereby complete the movement of said valve to its opposite seat, and it will be thrown from the position shown in Fig. 1 to that shown in Fig. 2, and vice versa. After the inlet valve becomes unseated and before it is completely thrown, the exhaust valves will be unseated by the stem 14 striking the abutment 2. This places said exhaust valves in a balanced position, but after the inlet valve has become entirely thrown, the live fluid will complete the throw of the exhaust valves by coming in contact with the head of one of the exhaust valves nearest the abutment. This will reverse the direction of the piston, as the direction of the flow of the motive fluid is reversed.

The operation may be described as follows: With the valves in the position shown in Fig. 1, the live fluid passes into chamber 4 through the hollow piston rod 6, and thence past the inlet valve 15 and into and through the tubular extension 16' to the interior of the cylinder, where it will exert itself to drive the piston to the left. In the meantime, the exhaust fluid passes the left exhaust valve into the chamber 5, from whence it passes into the hollow piston rod 9 and escapes through the outlet 10. When the piston approaches the end of its stroke, the end of the tubular extension 16 will engage the head or abutment 2 and thereby unseat the inlet valve 15. The live fluid, however, will not pass to the front of the piston as the end of the tubular extension 16 and the abutment 2 form an auxiliary valve. The piston will therefore, continue in its movement to the left while the exhaust valve stem 14 makes contact with the cylinder head or abutment 2 and unseats the exhaust valve. This places said exhaust valves in a balanced position and balances the pressure, of the fluid on both sides of the piston and said piston will be at rest. The live fluid exerting itself against the abutment 2 in the tubular extension 16, will then complete the movement of the inlet valve and allow the live fluid to pass to the side of the piston which is nearer the said abutment. The pressure of the live fluid on that side of the piston will then complete the movement of the exhaust valves and said piston will begin its movement in the opposite direction.

While I have shown and described the valves mounted in movable chambers, and the valves engaging stationary abutments, I do not wish to be understood as limiting

my invention to these particular features, 65 for the reason that the chambers may be stationary and the abutments movable without departing from the spirit of my invention.

I claim:

1. In a water motor, a cylinder, a piston, exhaust and inlet valves, abutments, said inlet valve and said abutments being constructed and arranged to coöperate to prevent the motive fluid from being reversed 75 when said inlet valve is unseated, thereby preventing said inlet valve from becoming balanced after it is unseated, and causing a complete reversal of the valves at each end of the piston stroke by the motive fluid, 80 the exhaust valve being initially moved by engagement with said abutments.

2. In a fluid motor, a cylinder, a piston, inlet and exhaust valves, abutments, said inlet valve being constructed and arranged 85 to coöperate with said abutments at each end of the piston stroke to form an auxiliary valve to prevent the motive fluid from being reversed until the exhaust valve is forced from its seat, thereby causing a complete reversal of the valves by the motive fluid.

3. In a fluid motor, a cylinder, a piston, abutments, exhaust valves, an inlet valve having tubular extensions coöperating with 95 said abutments to allow the piston to continue its movement after the inlet valve is unseated to unseat the exhaust valve, thereby causing a complete reversal of the valves by the motive fluid.

4. In a water motor, a motor chamber with a movable piston therein, means for supplying water to both sides of said piston, inlet and exhaust valves to control the supply and exhaust, with hollow stems for the 105 inlet valves projecting into the motor chamber on each side of said piston, with openings beyond the valve seats into said stems for the passage of the water, and to accumulate pressure to fully actuate said valves.

5. In a water motor, a motor chamber with a movable piston therein, means for supplying water to both sides of said piston, a double puppet valve to control said supply, hollow stems for said valves projecting into 115 the motor chamber on opposite sides of said piston, with openings beyond the valve seats into said stems for the passage of the water, and to accumulate pressure to fully actuate said valve and exhaust valves to control the 120 exhaust.

6. In a water motor, a motor chamber with a hollow piston movable therein, having an inlet and exhaust chamber, a double puppet inlet valve with hollow stems for 125 said valve projecting into the motor chamber, and having openings beyond the valve seats into said stems, said hollow stems

adapted to form between the piston and
motor chamber walls, a receptacle to ac-
cumulate water pressure on the inlet valve
upon the unseating of same, to fully actuate
5 said valve and an exhaust valve to control
the exhaust.

In testimony whereof I affix my signature,
in presence of two witnesses.

PETER T. COFFIELD.
